UNITED STATES PATENT OFFICE.

CARL E. CAPMAN, OF CHICAGO, ILLINOIS, ASSIGNOR TO JOSEPH SALTZMAN, OF CHICAGO, ILLINOIS.

IRONING-MACHINE.

1,340,522.

Specification of Letters Patent. Patented May 18, 1920.

Application filed October 27, 1917. Serial No. 198,748.

To all whom it may concern:

Be it known that I, CARL E. CAPMAN, a citizen of the United States, residing at Chicago, in the county of Cook and State 5 of Illinois, have invented certain new and useful Improvements in Ironing-Machines, of which the following is a specification.

My invention relates to improvements in ironing machines, and relates in particular 10 to a type of garment-pressing device, of the hand type, so organized as to require a minimum of bodily effort in the manipulation thereof.

The principal objects of the invention are 15 to provide a device of the class described which shall be free from ungainly and space-occupying overhead suspension devices; to provide a device of the class described which may be mounted conveniently 20 and in compact form upon the usual table on which the hand pressing is ordinarily effected; to provide a construction which shall be capable of quick and simple adjustment to accommodate different classes of 25 work,—for instance, for pressing coats, where a pressing buck is required, and for pressing trousers, where the pressing buck is dispensed with; to provide a construction which shall be substantial, convenient, and 30 practical, while being simple in design and economical to manufacture; and, in general, to provide an improved efficient device of the character referred to.

In the drawings, which illustrate a preferred embodiment of my invention—

Figure 1 is a plan view of the device and a portion of the table;

Fig. 2 is an end elevation of the table showing the device mounted thereon;

Fig. 3 is a section through the line 3—3 of Fig. 2; and Fig. 4 is a section taken on the line 4—4 of Fig. 2.

Referring to the drawings, 10 represents a large, heavy, and substantial table which 45 constitutes a support for the pressing device 11 and pressing buck 12. The device itself is preferably supported by a cast iron socket 14 having a foot or base plate 15 of suitable shape and dimensions to securely 50 hold the socket 14 in upright position. Said integral base plate 15 is suitably bolted to the table by means of coach screws or lag bolts 16, and a vertically extending tubular standard or pipe 17 is secured in the socket 55 14 by a set screw 18. This standard extends upward a considerable distance and carries

at its upper end a sponge bowl 19 secured thereto in any suitable manner, for instance, by a pin 20. Slidably and rotatably mounted upon the column 17 is a cast iron sleeve 60 21 which may be adjusted vertically by a collar 23, the latter being rigidly secured to the column 17 by means of a clamp screw 22.

At the upper and lower ends of the sleeve 65 21 there are pairs of spaced apart lugs 24 and 25 through which pass pivot pins 26 and 27 which are held in place by cotter pins 71 passing through the projecting ends of the pins. On said pivot pins 26 and 27 70 and between the said pairs of lugs 24 and 25, I pivotally mount a pair of parallel bars 28 and 29, which, at their outer ends, are pivotally secured at 30 and 31 respectively to a cast head 32. The pivot pin 31 is 75 secured in a bolt hole 72 at the bottom of the head 32, whereas the pivot pin 30 is so arranged that it may be adjusted in a slot 33 formed in the upper portion of said casting 32. To this end, the said pivot pin 30 is 80 made with an intermediate collar or enlargement 34 which may be clamped against the face of the slot 33 by means of a nut 37 fitting the threaded end 38 of the pivot pin and bearing against a washer 70 placed against the 85 outer face of the cast head. The pivot pin 31 is like the pin 30 and is secured to the head 32 in the same manner, except that an ordinary bolt hole 72 is provided in the head 32 for the pin 31, instead of the slot 90 33, as in the case of the pin 30. These pins 30 and 31 each have a washer 35 and a cotter pin 36 for holding the ends of the respective arms 28 and 29 thereon for pivotal movement.

On one side of the cast head 32 there are formed a pair of integrally cast, semi-circular housing 38 and 39, which accommodate laterally and vertically spaced pulleys 40 and 41 arranged to revolve idly upon 100 fixed pivot pins 42 and 43. Said pulleys 40 and 41, as shown in Figs. 1 and 2, are grooved to fit a horizontally slideable rod 44 which is preferably of circular cross-section, so as to enable it to twist slightly if 105 occasion requires. As shown in Fig. 2, the pulley 40 constitutes a lower support for the outer end of the rod 44 and parts carried thereby, while the rear pulley 41 constitutes an abutment for the rear end of the 110 rod 44 and prevents it from tipping forward. The usual tailor's goose or pressing

iron 45 is carried on the forward or front end of the rod 44.

Describing the manner of attaching the pressing iron to the front end of the rod 44, it will be observed by an inspection of Fig. 1, that on the top plate 46 of the iron I secure, by means of rivets or screws 47, a strap-like bracket 48 which is perforated the lower end of the perforation being suitably countersunk to constitute a downwardly facing seat for a socket ball 50. Said socket ball 50 is rigidly secured on the end of a slender curved rod 51, the tail end of which is rigidly secured in a longitudinal hole 15 drilled in the tapered front end 52 of the horizontal bar 44. This construction allows the iron to assume any angular position, while at the same time the weight of the iron is effectually supported by the ball-and-socket arrangement. It is of course understood that the ball-and-socket is positioned approximately above the center of gravity of the pressing iron.

The pressing iron, which, in the present instance, is of the gas-heated type, is supplied with gas through a hose 53 which, if desired, may be passed through an eye-bolt 54 secured in the rear end of the slide rod 44.

30 When the pressing iron is not in use and is therefore suspended in mid-air by the supporting device, the equilibrium of the apparatus is maintained by means of a diagonally disposed coiled tension spring 55, the rear end of which passes through an eye-bolt 56 secured in the upper end of the bar 28, while the lower end of said spring 55 is hooked into the upper end of a diagonal link or tie 57 constructed from wire or rod 35 of suitable gage. The lower end of said link 57 is bent around to form a hook portion 58 suitably shaped to enter one or other of a pair of notches 59 and 60 in the lower end of the head 32. To facilitate shifting of the 40 hook part 58 from one end to the other of the notches 59 and 60, the end of said hook 58 is extended and bent to form a crook part 61 which fits the finger. The object of such adjustment is to tighten or loosen the spring 45 depending upon whether it is desired to suspend the iron in an upper position suitable for pressing with the buck, or in a lower position suitable for pressing on the surface of the table.

55 The operation of the device is practically self-evident, in view of the above description. When the iron is quiescent and suspended, the rod 44 is preferably pushed in horizontally between the pulleys 40 and 41 60 to approximately the position shown in Fig. 2, and in that position for pressing with the buck, the spring is of such strength as to maintain the pressing surface of the iron about a couple of inches below the top of 65 the buck. When the iron is moved onto the

adjacent end of the buck for pressing clothes thereon, the spring greatly facilitates the upward movement of the iron and relieves the operator of the necessity of exerting a great amount of manual force when lifting the 70 iron. The spring is of such strength that when the iron is thus lifted onto the buck, the spring is almost totally collapsed and consequently the full weight of the iron is available for pressing.

75 With the arrangement described, the movement of the iron over the clothes to be pressed is extremely free and is not interfered with by cramping frictional stress or other forces, it being understood that as the 80 iron is manipulated, the parallels swing around the column 17 with the sleeve 21, in addition to which the rod 44 slides in and out between the pulleys 40 and 41.

85 The object of having the pin 30 adjustable in the arcuate slot 33 is to enable the rod 44 to be leveled up, or, in certain cases, inclined, whenever occasion requires.

The hereinbefore specified details of construction are of course subject to change or 90 modification, in order to conform to individual requirements, while still retaining the spirit of the invention, the scope of which should be determined by reference to 95 the appended claims.

I claim—

1. In a device of the class described, the combination of an upstanding column, a member rotatably mounted on said column, a head, parallel bars pivotally connecting the upper end of the head to the upper end of the member, and the lower end of the head to the lower end of the member, an iron supported by said head, and a spring 100 for facilitating the vertical movement of 105 said head.

2. In a device of the class described, the combination of a vertical supporting column, a member mounted on and rotatable around said column, means for vertically adjusting 110 said member, a head, parallel bars connecting said head with said member and permitting relative vertical displacement thereof, a spring tending to support said head, a substantially horizontal rod slidable in said 115 head, and an iron pivotally carried at the outer end of said rod.

3. In a device of the class described, the combination of a vertical supporting column, a member mounted on and rotatable 120 around said column, means for vertically adjusting said member, a head, parallel bars connecting said head with said member and permitting relative vertical displacement 125 thereof, an adjustable spring tending to support said head, a substantially horizontal rod slidable in said head, an iron pivotally carried at the outer end of said rod, and means for adjusting the inclination of said rod.

CARL E. CAPMAN.
